ENGINE STARTER GEARING

James E. Buxton, Elmira, N. Y., assignor to Bendix Aviation Corporation, Elmira Heights, N. Y., a corporation of Delaware

Application June 23, 1954, Serial No. 438,663

5 Claims. (Cl. 290—38)

The present invention relates to engine starting gearing and more particularly to that type in which a motor driven pinion is shifted into and out of mesh with an engine gear, partly by longitudinal movement of the armature shaft of the motor, and partly by axial movement of the pinion on the motor shaft.

It is an object of the present invention to provide a novel starter gearing of the above type in which the pinion is held in mesh with the engine gear until both the engine and the starting motor have simultaneously exceeded a predetermined speed of rotation.

It is another object to provide such a device which is efficient and reliable in operation and simple and economical in construction and assembly.

Further objects and advantages will be apparent from the following description taken in connection with the accompanying drawing in which:

Fig. 1 is a side elevation, partly broken away and in section, of a preferred embodiment of the invention showing the parts in idle position; and

Fig. 2 is a similar view showing the parts in cranking position.

In Fig. 1 of the drawing there is illustrated a starting motor 1 comprising a stationary field 2 and a rotatable armature 3 having a shaft 4 which is mounted for rotary and limited longitudinal movement in bearings in the 40 ends of the motor 1, one of which is shown at 5. The armature shaft 4 is extended outward beyond the bearing 5, and its outer end supported in an outboard bearing 6 attached to the motor frame as indicated at 7.

A pinion 8 is slidably journaled on the armature shaft 45 for movement into and out of mesh with an engine gear 9, and means for actuating the pinion from the armature shaft is provided comprising a hollow sleeve 11 fixed as indicated at 12 to the armature shaft and having an anchor plate 13 non-rotatably mounted thereon and connected by a drive spring 14 to a similar anchor plate 15 non-rotatably fixed on a driving overrunning clutch member 16 which is slidably journaled on the sleeve 11.

A hollow screw shaft 17 having driven overrunning clutch teeth 18 cooperating with similar teeth 19 on the clutch member 16 is also slidably journaled on the sleeve 11, and a control nut 21 threaded on the screw shaft is rigidly connected to the pinion 8 by a barrel member 22.

Longitudinal movement of the driving clutch member 16 toward the engine gear 9 is limited by a thrust ring 23 seated in a groove 24 in the sleeve 11 and received by a counter bore 25 in the clutch member. The ring 23 is so located as to maintain the drive spring 14 under a small amount of initial compression between a flange 26 on the sleeve 11 and a flange 27 on the clutch member 16. Movement of the clutch member 16 in a direction to compress the drive spring 14 is limited by a shoulder 28 and thrust washer 29 on the sleeve 11.

Movement of the screw shaft 17 toward the engine 70 gear 9 is limited by a stop ring 31 fixedly mounted on

2

the end of the sleeve 11. A spring washer 33 and thrust ring 34 are interposed between the end of the screw shaft 17 and the stop ring 31 in order to yieldingly urge the screw shaft into clutching engagement with the clutch member 16.

Means for limiting the demeshing movement of the control nut 21 is provided in the form of shoulders 35 on the ends of the threads of the screw shaft, and a spring pressed detent 36 is mounted for radial movement in 10 the control nut to frictionally engage an inclined surface suitably located on the screw shaft to prevent the pinion from drifting away from its idle position.

The armature 3 is normally held in a decentered position relative to the field 2 of the motor by means of a spring 37 which bears at one end against the motor bearing 5, and at its other end against the bottom of a cup member 38 fixed on the armature shaft 4. Expansion of the spring 37 is limited by the engagement of the flange 26 of sleeve 11 against the outer side of the motor bearing 5, a thrust washer 39 being preferably interposed. In order to yieldably hold the armature in centered relation to the motor field, the exterior of the motor bearing 5 is provided with an annular groove 41, and a detent 42 is mounted for radial movement in the cup member 38 in position to enter the groove 41 when the armature is in centered position. A spring 43 is arranged to press the detent 42 into the groove 41, and is so calibrated with respect to the mass of the detent that the detent will be withdrawn radially from the groove 41 by centrifugal force when the armature rotates above a predetermined speed. The detent 42, and the end of the motor bearing 5 are suitably beveled as indicated to permit the detent to slide into the groove 41 when the armature is drawn toward its centered position by initial actuation of the starting motor.

In operation, starting with the parts in the positions as illustrated in Fig. 1, energization of the starting motor causes its field 2 to magnetically draw the armature 3 into centered position against the action of the spring 37, where it is maintained by engagement of the centrifugal detent 42 in the groove 41. This movement of the armature shaft 4, being transmitted to the pinion 8 through the spring 14, screw shaft 17, control nut 21, and barrel 22, moves the pinion into initial meshing engagement with the engine gear 9. Concurrently with this longitudinal movement, rotation of the armature commences and being transmitted to the screw shaft 17 causes the control nut 21 to be traversed further until its movement is arrested by the stop ring 31, at which time the pinion 8 is fully meshed with the engine gear 9. The consequent transmission of torque through the drive sets up a screwjack action between the screw shaft and control nut which moves the screw shaft backward, forcing together the clutch teeth 18, 19 and compressing the spring 14 until the backward movement of the clutch member 16 is arrested by the shoulder 28 on the sleeve 11. Thereafter torque is yieldably transmitted through the drive spring 14 to crank the engine.

When the engine fires, the acceleration of the pinion 8 causes the control nut 21 to overrun the screw shaft 17, threading itself back to idle position thereon, after which the screw shaft is caused to overrun the clutch member 16. The pinion 8 however remains in partial mesh with the engine gear 9 so that if the engine does not continue to be self-operative, cranking will be resumed as soon as the engine speed falls below the corresponding speed of the starting motor.

When a successful start of the engine has been secured, the release of the load on the starting motor permits it to accelerate sufficiently to cause the detent 42 to be withdrawn by centrifugal force from the groove

41. The spring 37 thereupon becomes operative to move the armature back toward its decentered position, which is permitted due to the fact that the high speed of rotation of the idly rotating motor increases the counter electro-motive-force of the motor to a point where the centering attraction of the field for the armature is greatly reduced. Deenergizing of the starting motor thereafter permits the parts to return to idle position.

Although but one form of the invention has been shown and described in detail it will be understood that changes may be made in the precise form and arrangement of the parts without departing from the spirit of the invention.

I claim:

1. In an engine starter a motor having a stationary field and a rotatable armature which is shiftable longitudinally into and out of centered position with respect to the field, an armature shaft, a pinion slidably and rotatably mounted thereon for movement thereon and therewith into and out of mesh with a gear of an engine to be started, means for actuating the pinion from the armature shaft including a screw shaft rotatably and slidably mounted on the armature shaft, a control nut threaded thereon rigidly connected to the pinion, an overrunning clutch connection from the armature shaft to the screw shaft, yielding means urging the armature shaft toward its decentered position, and means including a mounting member fixed on the armature shaft and a centrifugal detent carried thereby for resisting decentering movement of the armature shaft below a pre-determined speed.

2. An engine starter as set forth in claim 1 in which

the overrunning clutch connection to the screw shaft includes a driving dental clutch member, yielding driving means for actuating the clutch member from the armature shaft, and means responsive to the screw-jack action of the screw-shaft and control nut for compressing the overrunning clutch.

3. An engine starter as set forth in claim 2 including further a stop ring fixed on the armature shaft defining the operative position of the control nut, and an abutment on the armature shaft limiting the movement of the driving clutch member away from the control nut during the cranking operation.

4. An engine starter as set forth in claim 3 including further abutment means fixedly mounted on the armature shaft limiting movement of the driving clutch member toward the screw shaft, and a spring between the screw shaft and said stop ring urging the screw shaft into clutching engagement with the driving clutch member.

5. An engine starter as set forth in claim 1 in which the means for resisting decentering movement of the armature shaft comprises a bearing member fixed to the frame of the starting motor having a boss in telescopic relation with said mounting member, and having a circumferential groove, and said centrifugal detent is arranged to register with said groove when the armature is in centered relation to the motor field.
